UNITED STATES PATENT OFFICE

JOHN T. COONEY, OF RESEDA, CALIFORNIA

TOY

Application filed May 17, 1929. Serial No. 363,798.

This invention relates to improvements in toys and has particular reference to a toy or amusement device adapted to be attached to a moving vehicle.

5 The principal object of the invention is to produce a toy which will simulate all of the movements of a regular airplane, such as straightaway flight, rising and lowering, barrel roll, etc.

10 A further object is to produce a device which is economical to manufacture and therefore one which may be sold at a very low cost.

15 Other objects and advantages will be apparent during the course of the following description.

In the accompanying drawings forming a part of this specification and in which like numerals are employed to designate like parts 20 throughout the same,

Figure 1 is a fragmentary perspective view of the front of a vehicle having my invention applied thereto,

25 Figure 2 is an enlarged detail perspective view of my device, and

Figure 3 is an enlarged underside fragmentary view of the toy.

Many forms of removable devices have been used on the front of a vehicle which devices are adapted to be engaged by the wind caused by the travel of the vehicle, which devices rotate or cause some fantastic movement which is pleasing to the eye. Applicant has sought to employ this wind pressure 30 in order to cause a tiny airplane to ride from end to end of a cord and during the movement to assume various airplane positions which are caused by the variance in wind pressure from one side or the other.

40 In the accompanying drawings wherein for the purpose of illustration is shown a preferred embodiment of my invention, the numeral 5 designates a motor vehicle as a whole, the numeral 6 the radiator thereof and the

45 numeral 7 the visor adjacent the wind shield. While the string is shown in this instance connected to the visor it is obvious that the same may be connected to the wind shield. I prefer to employ a suction cup 8 to which a cord 50 9 is adapted. A stop is placed upon the cord

as shown at 11 and a similar stop is provided at 12. The opposite end of the cord is connected to the radiator cap 13 or may be secured at any other convenient spot.

The primary function of the cord is to 55 carry the airplane and it should be disposed at an angle of substantially 45 degrees. The airplane consists of a flat blank 14 having a wing surface 16 and a tailed surface 17. An upwardly extending fin 18 is pivoted as at 19. 60 This pivot may be actual or merely a flexible connection. An eye 21 is connected to the fin 18 and is slidable upon the cord 9. A similar eye 22 is connected to the forward 65 end of the plane and is also slidable upon the cord. On the bottom of the plane I secure a cone-shaped piece 23 which gives the lower surface of the plane a considerable thickness and therefore assists in the raising operation.

A propeller is shown at 24 which is rotatable on the cord 9 but has no connection with the plane and is merely kept there-against by the action of the wind or sliding of the plane. Assuming that the device is attached to a vehicle as shown in Figure 1 and the vehicle is 70 moving along the highway, the air pressure will in some instances cause the propeller 24 to rotate and by striking the front of the plane and the cone 23, will cause the plane to move rearwardly toward the wind shield. If 75 the speed of the vehicle is reduced the plane will slide down toward the radiator and when side currents strike the plane from either one side or the other, various maneuvers will be caused to occur which will simulate the 80 maneuvers of an ordinary plane.

It is to be understood that the form of my invention herewith shown and described is to be taken as a preferred example of the same and that various changes relative to the material, size, shape and arrangement of parts may be resorted to without departing from the spirit of the invention or the scope of the subjoined claim.

Having thus described my invention, I 95 claim:

In a device of the character described adapted to be attached to a moving vehicle, a cord angularly disposed with respect to a horizontal, a plane movable on said cord and 100

suspended therefrom, a freely rotatable propeller movable on said cord and independently of said plane whereby said propeller may move toward or away from said plane or

5 along said cord therewith.

5 In testimony whereof I affix my signature.

JOHN T. COONEY.
